UNITED STATES PATENT OFFICE.

THOMAS F. DENNISON, OF PASSAIC, NEW JERSEY.

GUIDE FOR SEWING-MACHINES.

1,109,404.

Specification of Letters Patent.

Patented Sept. 1, 1914.

Application filed November 19, 1912. Serial No. 732,243.

To all whom it may concern:

Be it known that I, THOMAS F. DENNISON, a subject of the King of Great Britain, and a resident of Passaic, in the county of Passaic and State of New Jersey, have invented a new and Improved Guide for Sewing-Machines, of which the following is a full, clear, and exact description.

The invention relates to sewing machines mounted one alongside the other on a bench and used for hemming handkerchiefs or similar articles in the piece.

The object of the invention is to provide a new and improved guide mounted on the bench opposite the feeding side of the sewing machine for guiding the piece of goods to the hemmer of the sewing machine, the guide being arranged to permit of moving it away from the feeding side of the sewing machine to allow convenient access to the machine for removing the machine from the bench for repairs or other purposes.

In order to accomplish the desired result, the bench is provided with a bracket on which the guide is mounted to swing into and out of working position relative to the sewing machine, and locking means for normally locking the guide to the bracket to hold the guide in proper position relative to the sewing machine.

A practical embodiment of the invention is represented in the accompanying drawings forming a part of this specification, in which similar characters of reference indicate corresponding parts in all the views.

Figure 1 is a perspective view of the guide as applied to a bench carrying a number of sewing machines, the guide being in open position relative to its particular sewing machine; Fig. 2 is a plan view of the same and showing the guide in normal active position; and Fig. 3 is a cross section of the bench and showing the guide and sewing machine in elevation.

In factories making handkerchiefs and other similar articles in the piece, requiring hems or seams, a number of sewing machines having hemming attachments are mounted on a bench with sufficient space between adjacent sewing machines to accommodate the operators and the work. Guides for guiding the work to the hemmers are mounted on the bench immediately opposite the feeding side of the sewing machine, and the said guides prevent convenient access to the sewing machines for making slight

repairs. The guides extend somewhat above the level of the bench and in case it is desired to remove a sewing machine for making heavy repairs or for other purposes it is necessary to lift the sewing machine off the bench and over the guide. As the sewing machines are heavy considerable physical exertion is required on the part of the operator to lift the sewing machine over the guide, and in doing so the sewing machine is liable to strike the guide and injure the same. In order to overcome this objectionable feature use is made of a guide, presently to be described in detail, which can be moved temporarily out of its normal position for giving convenient access to the sewing machine.

A number of sewing machines A are mounted on a bench B with sufficient space between the sewing machines to readily accommodate the operators and the work. From the bench B extends forwardly a bracket C adjacent each sewing machine A, and this bracket C supports a guide D by the use of hinges E connecting the guide D with the outer vertical member C of the bracket C. The guide D comprises a frame carrying guide bars for guiding the fabric to the sewing machine, the hinges E being at one side of the frame. The hinges E have their pintles E' disposed vertically to permit of swinging the guide D from a normal closed position, which is parallel to the bench B, outward into an angular or open position, as indicated in Fig. 1. The guide frame D, as shown in the drawing is provided with projecting brackets D' on its side members near the upper end thereof, having vertical pins D² on which a guide bar D³ is supported. An angular bracket D⁴ projects from one side member of the guide frame D and has an adjustable member D⁵ thereon to which a guide D⁶ is secured. The fabric F to be hemmed extends loosely from a receptacle G containing the fabric in folds or in the form of a bolt. The fabric passes upward over the guide bar D³ then under and over the top member of the guide frame D and then under the guide bar D⁶, as shown in Fig. 3, and is thus guided to the hemmer H of the sewing machine so that one side edge of the fabric F is provided with a hem by the action of the sewing machine and the hemmer H. The fabric after leaving the sewing machine A passes over a

roller I mounted at the rear edge of the bench B and then the fabric slides down over a guide J into a second receptacle G' in which the fabric accumulates. When 5 the fabric has been run through the machine and one side has been hemmed then the positions of the receptacles G and G' are changed so that the receptacle G' takes the place of the receptacle G and the latter is placed in the position previously occupied by the receptacle G'. The fabric is now again run from the receptacle G' up over the guide bars of the frame D to and through the hemmer H to receive a hem 15 on the other side edge, the fabric being finally deposited in the receptacle G.

The guide D is provided with a spring catch K adapted to engage the vertical member C' of the bracket C at the time 20 the guide is in normal working position, as shown in Figs. 2 and 3, so that the guide is held locked in this normal position. When it is desired to make slight repairs on the sewing machine A the mechanic unlocks the guide D by disengaging the catch K from the bracket member C' and then 25 swings the guide D outward to obtain access to the sewing machine A for conveniently making repairs thereon.

30 If it is desired to remove the sewing machine A from the bench B for making heavier repairs or for other purposes, the guide D is likewise swung into an open position to permit convenient removal of the sewing 35 machine A from the bench B without lifting the sewing machine over the guide, which latter, as indicated in Fig. 3, extends with its top a considerable distance above the level of the bench B. After the 40 repairs have been made the frame D is swung shut, that is, back into operative position and is locked then by the catch K engaging the bracket C.

Having thus described my invention, I 45 claim as new and desire to secure by Letters Patent:

1. In a guide for sewing machines, a forwardly extending bracket secured to a support adapted to carry a sewing machine, the said bracket having a vertical member 50 at its outer or forward end, a guide comprising a frame provided with guide bars, hinges connecting the frame at one side to the vertical member of the said bracket, 55 the said guide when in normal or closed position extending in front of and parallel with the feeding side of the sewing machine

for guiding the fabric to the sewing machine, the hinges having their pintles disposed vertically to permit of swinging the 60 guide from the normal closed position outward into an open position to one side of and at an angle to the sewing machine, and a spring catch on the guide frame adapted to engage the vertical member of 65 the bracket to hold the guide in normal working position.

2. In a guide for a sewing machine, the combination with a bench adapted to support a sewing machine, of a bracket extending forwardly from said bench, a rectangular guide frame hinged at one side on the outer end of said bracket, the hinges having their pintles disposed vertically to permit of swinging the frame into normal or 70 closed position parallel to the bench and in front of the feeding side of the sewing machine, or into an open position to give access to the sewing machine, horizontal 75 guide bars carried by said guide frame, the said bars when the frame is in the closed position guiding the fabric to the sewing machine, and means for locking the guide frame to the bracket when the guide frame is in closed or working position.

3. A guide for sewing machines, comprising a vertically arranged frame provided with projecting brackets on its side members near the upper ends thereof, the said brackets having vertical pins, a horizontal 90 guide bar supported at its ends on said pins, an angular bracket projecting from one side member of the frame and having an adjustable member thereon, a horizontal 95 guide bar secured to said adjustable member, the said guide bar being in a lower plane than the first guide bar and spaced a greater distance from the face of the frame, and means for pivotally supporting the frame at one side to permit of swinging the frame into closed position in front of the feeding side of the sewing machine, or into an open position to give access to 100 the sewing machine, the said guide bars when the frame is in the closed position serving to guide the fabric to the sewing machine.

In testimony whereof I have signed my name to this specification in the presence of two subscribing witnesses.

THOMAS F. DENNISON.
